UNITED STATES PATENT OFFICE.

CHARLES F. STODDARD, OF BOSTON, MASSACHUSETTS.

AUTOMATIC MUSICAL INSTRUMENT.

1,254,082.

Specification of Letters Patent. Patented Jan. 22, 1918.

Application filed November 20, 1911. Serial No. 661,232.

To all whom it may concern:

Be it known that I, CHARLES F. STODDARD, a citizen of the United States, and a resident of Boston, county of Suffolk, and State 5 of Massachusetts, have invented an Improvement in Automatic Musical Instruments, of which the following description, in connection with the accompanying drawings, is a specification, like characters on the 10 drawings representing like parts.

This invention relates to automatic musical instruments of the type in which the playing is controlled by a perforated note sheet or the like, wound from a spool onto 15 a take-up roll; and the invention pertains more particularly to an automatic stop mechanism for arresting the operation of part or all of the apparatus, by reference to the rewinding of the note sheet.

20 The character of the invention may be readily understood by reference to one practicable embodiment which is shown by way of illustration in the accompanying drawings, in which:

25 Figure 1 is a diagrammatic representation of a stop mechanism for throwing an electric switch to break a motor circuit, when the music sheet has been re-wound from the take-up roll onto the spool upon completion 30 of a playing operation;

Fig. 2 diagrams suitable circuit arrangements illustrating the practice of the invention.

As shown in Fig. 1, the illustrative take-up roll 5 is provided with a duct 6 opening 35 at the surface of the roll and adapted to be covered by the note sheet while the latter is being wound thereon. The duct 6 may be arranged radially of the take-up roll 5 and 40 to communicate with a duct 7 which extends axially through the shaft 8 of the take-up rolls and communicates with a mating duct 9 in the bearing 10 for said shaft. The bearing 10 may be of any practicable 45 design. The duct 9 is preferably extended as by a tube 11 to a diaphragm chamber 12 which controls a double-acting valve 13. The valve 13 controls a port 14 to atmosphere and a port 15 to an exhaust chamber 16 connected by a duct 17 with any practicable source of exhaust. A bleeding vent 18 is interposed between the diaphragm chamber 12 and exhaust chamber 16. The ports 14 and 15 are opened alternatively by the

valve 13 into communication with the interior of a pneumatic 20. The movable board of the pneumatic 20 is suitably connected as by links 21, 22, with a stopping device of suitable construction and mode of operation to suit the particular apparatus 55 for which the invention is to be applied as exemplified by an electric switch 23 of the well known two-button type in which one of the two buttons is intended to be pressed for breaking the circuit and the other button to be pressed for making the circuit. The illustrative switch 23 has the button 24 which, when pressed in, makes the circuit by swinging a contact lever 24^a clockwise in Fig. 1 about its pivot 24^b. This lever 70 is provided at its upper end with a contact 24^c insulated from the rest of the lever, and always in frictional contact with a fixed contact 24^d secured to the interior of the casing of the switch 23 from which it is insulated. When moved as described, the contact 24^c also contacts frictionally with a second fixed contact 25^b secured to the interior of the casing of the switch 23 and 75 insulated therefrom. When said button 24 is pulled out the circuit will be broken as will be readily understood with an effect equivalent to that of pressing in the other button 25. The link 22, for example, is connected to the button 24. Hence, when the 80 pneumatic 20 is collapsed it pulls the links 21 and 22 toward the left in Fig. 1 and thereby pulls out the button 24 and breaks the circuit through the switch.

Preferably, some manually operable means 90 is provided for controlling the switch; for example, a hand lever 25^a is fulcrumed at 26 and the links 21 and 22 connected thereto. When the pneumatic 20 is collapsed automatically, the hand lever 25^a swings idly, 95 and when it is desired to re-make the circuit by pushing in the button 24, the hand lever 25^a may be swung contraclockwise in Fig. 1 for that purpose.

Referring now to Fig. 2, the above described illustrative apparatus is shown in connection with the take-up roll 5 and other parts described. The take-up roll receives the note sheet 30 from the spool 31 after passing over the tracker 32. This apparatus 105 is illustrated as employed for the purpose of controlling a motor circuit 35 comprising a source of power 36 and an electric motor

37 which is belted to suitable means for operating feeder bellows 38 by which the pneumatic action of the instrument is exhausted through a trunk 39.

5 The operation of the illustrative preferred apparatus is as follows:

The note sheet being partially unwound from the spool 31, is wound upon the take-up roll 5 sufficiently to close the duct 6. Thereupon the feeder bellows 38 is started in operation as by throwing the hand lever 25^a contraclockwise in Fig. 1 to the position shown, to close the circuit to the motor 37. This exhausts the pneumatic action and starts the drive of the note sheet winding mechanism through a pneumatic motor for instance, (not shown) which communicates directly or indirectly with the trunk 39. Likewise, the trunk 39 being connected directly or indirectly with the duct 17, the exhaust chamber 16 is evacuated and through the bleed 18 the diaphragm chamber 12 is likewise evacuated, the valve 13 being then held in the position shown. This condition continues (unless changed by operating the hand lever 25^a) so long as the note sheet remains wound upon the take-up roll 5 sufficiently to cover the mouth of the duct 6. On the re-winding of the note sheet, however, the end of the latter is finally sufficiently withdrawn from the take-up 5 to vent to atmosphere the mouth of the duct 6, whereupon atmosphere enters the diaphragm chamber 12, lifts the valve 13, and opens communication between the exhaust chamber 16 and the interior of the pneumatic 20. This collapses the pneumatic 20, pulls the links 21, 22, and the button 24 to the left, and breaks the circuit through the illustrative switch 23 which constitutes a preferred form of stopping device.

It is to be understood that the invention is not limited to the specific construction, organization and mode of operation hereinbefore described, since, as will appear to those skilled in the art, the invention is susceptible of embodiment in various ways. It is not essential that the invention be employed in connection with the control of a feeder bellows motor nor in connection with any particular arrangement of electric or pneumatic circuit.

Claims:

1. In an automatic musical instrument, 55 the combination of a spool for the note sheet; a tracker; a take-up roll to receive the note sheet from the spool and having a vent in the surface thereof adapted to be closed when the note sheet is wound thereon; 60 a diaphragm chamber; a duct connecting the diaphragm chamber with the vent of the take-up roll; a valve controlled by the diaphragm of said chamber; a pneumatic collapsible upon operation of said valve; a handle lever connected to the movable board

of said pneumatic; an electric switch connected to said handle lever; feeder bellows; and a feeder-bellows electric motor having its circuit controlled by said electric switch.

2. In an automatic musical instrument, 70 the combination of a spool for the note sheet; a tracker; a take-up roll to receive the note sheet from the spool and having a vent in the surface thereof adapted to be closed when the note sheet is wound thereon; a diaphragm chamber; a duct connecting the diaphragm chamber with the vent of the take-up roll; a valve controlled by the diaphragm of said chamber; a pneumatic collapsible upon operation of said valve; a handle lever 75 connected to the movable board of said pneumatic; a stopping-and-starting device also connected to said handle lever; and a motor controlled by said stopping-and-starting device.

3. In an automatic musical instrument, the combination of a spool for the note sheet; a tracker; a take-up roll to receive the note sheet from the spool and having a vent in the surface thereof adapted to be closed when 90 the note sheet is wound thereon; a diaphragm chamber; a duct connecting the diaphragm chamber with the vent of the take-up roll; a valve controlled by the diaphragm of said chamber; a pneumatic collapsible 95 upon operation of said valve; a starting-and-stopping means connected to said pneumatic; and a motor controlled by said starting-and-stopping device.

4. In an automatic musical instrument, 10 the combination of a spool for the note sheet; a tracker; a take-up roll to receive the note sheet from the spool and having a vent in the surface thereof adapted to be closed when the note sheet is wound thereon; 105 a pneumatic collapsible upon opening said vent; transmitting means intermediate the vent and pneumatic; a stopping device operated by collapse of said pneumatic; and a motor controlled by said stopping device.

5. In an automatic musical instrument, the combination of a spool for the note sheet; a tracker; a take-up roll to receive the note sheet from the spool and having a vent in the surface thereof adapted to be governed 115 and closed by the note sheet; a stop-mechanism controlled by said vent whenever the latter is uncovered by the note sheet during the operation of the machine; and manually operable means for operating the stop-mechanism independently of said vent.

6. In an automatic musical instrument, the combination of a spool for the note sheet; a tracker; a take-up roll to receive the note sheet and the spool and provided with a 125 controlling element of a stop-mechanism rendered inoperative when the note sheet is wound on the take-up roll; a stop-mechanism automatically operated by said controlling element whenever the note sheet is unwound 130

from the take-up roll; and a manually operable device for operating said stop mechanism.

7. In an automatic musical instrument, 5 the combination of a take-up roll having a duct in the body thereof extending from a point on the surface adapted to be covered by the note sheet, to a point contiguous to the bearings of the roll; a duct in the bearings 10 to communicate with the duct of the roll; an electric switch; and pneumatic

transmission mechanism intermediate said ducts and electric switch for operating the latter.

In testimony whereof, I have signed my 15 name to this specification, in the presence of two subscribing witnesses.
